DOOR LOCKING ASTRAGAL

Kurt P. Tschaepe, New York, N. Y.

Application February 23, 1950, Serial No. 145,620

3 Claims. (Cl. 20—21)

1

The present invention relates to new and useful improvements in door locking devices and more particularly to an astragal for sealing and locking the edge of a swinging door.

An important object of the invention is to provide a vertical astragal which may be mounted for horizontal sliding movement at either edge of a swinging door for entering a groove in an adjacent door structure to lock the door and seal the edge thereof together with means for automatically retracting the astragal to release the door for free swinging movement by a predetermined opening force subjected to the door.

Another object of the invention is to provide means for locking the astragal against movement to secure the door in its locked position.

A still further object is to provide a door locking mechanism for double swinging doors and including upper and lower sliding bolts for locking one of the doors and providing a horizontally slideable astragal carried by the other door for sealing and locking the meeting edges thereof and also providing means actuated by the astragal to lock the upper and lower bolts of the first named door.

A still further object is to provide an apparatus of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a vertical sectional view of the meeting edges of the double swinging doors and showing the individual locking mechanisms for each door;

Figure 2 is an enlarged fragmentary vertical sectional view showing the locking mechanisms at the upper edges of each door;

Figure 3 is a top plan view of the meeting edges of the doors and with the cover plates at the top of the doors removed;

Figure 4 is a fragmentary view in elevation of the meeting edge of one door provided with a seat for the astragal releasing roller of the other door;

Figure 5 is a similar view of the second door showing the astragal releasing roller;

Figure 6 is an enlarged fragmentary sectional

2

view taken on the line 6—6 of Figure 1 and showing the astragal in sealing position at the meeting edges of the doors when the doors are unlocked;

5 Figure 7 is a similar view showing the astragal in sealing position when the doors are locked, and;

Figure 8 is an enlarged fragmentary vertical sectional view taken on the line 8—8 of Figure 10 and showing the key controlled lock for the astragal.

Referring now to the drawings in detail wherein for the purpose of illustration I have disclosed a preferred embodiment of the invention,

15 the numerals 5 and 6 designate a pair of swinging doors or other double swinging closures, such as French doors, casement windows or the like, the door 5 being provided at its meeting edge with a horizontally slideable vertically extending astragal 7 for entering a vertical slot or groove 8 in the meeting edge of door 6.

Upper and lower slides 9 and 10 are slidably mounted in recesses 11 and 12 at the upper and lower edges of door 5 and are connected to the adjacent ends of astragal 7 by apertured ears 13 carried by the slides for receiving pins 14 passing transversely through the astragal and into the opening of the ears. Each sliding block 9 and 10 is provided with a rearwardly extending rod 15 slidable in a guide 16 with a coil spring 17 surrounding the rod or pin 15 and bearing against the rear of the slide to move the slide and astragal outwardly at the edge of the door.

35 Each slide 9 and 10 is also formed with a vertical opening 18 in which the upper end 19 of a bell crank lever 20 is loosely positioned to provide limited play for the end 19 of the lever in the opening 18. Lever 20 is pivoted to door 5 by a pin 21 and the opposite end of lever 20 extends in a rearwardly inclined position as shown at 22 and is formed with a longitudinal slot 23.

The upper bell crank lever 20 for the upper slide 9 is connected to the upper end of a rack bar 24 by means of a pin 25 carried by the rack bar and engaged in slot 23 of the bell crank lever and the lower bell crank lever 26 for the lower slide 10 is connected to the lower end of the rack bar 27 in a similar manner to rack bar 24.

50 Rack bar 24 extends downwardly at the free edge of door 5 and rack bar 27 extends upwardly at the free edge of door 5 and are formed with teeth 28 and 29 respectively engaging the diametrically opposite sides of a pinion gear 30 secured to the inner end of a rotary lock cylin-

der 31 which is rotatably mounted in a conventional type of lock barrel or casing 32 to which the cylinder 31 is locked by a key 33 in the usual manner.

The adjacent ends of rack bars 24 and 27 and pinion gear 30 are mounted in a housing 34 recessed in the central portion at the free edge of door 5, the rack bars being slidable in the housing.

Upper and lower vertically sliding bolts 35 and 36 are positioned adjacent the free edge of door 6 with the upper end of upper bolt 35 positioned for entering a bolt socket 37 in the header 38 of the door frame and the lower end of lower bolt 36 being positioned for entering a bolt socket 39 in the door sill 40.

The lower end of upper bolt 35 and the upper end of lower bolt 36 are slidably mounted in a housing 41 recessed in the free edge of door 6 and the adjacent ends of the bolts are formed with rack bars 42 and 43 respectively positioned at diametrically opposite sides of a pinion 44 journaled in the housing 41. The pinion 44 is formed with a central hexagonal opening 45 to receive a suitable tool for turning the pinion, or by means of which a handle or door knob may be secured to the pinion for turning the same.

Upper and lower slides 9 and 10 of door 5 are provided with rollers 46 and 47 each journaled on a pin 48 carried by the slide to rotatably support the rollers in a horizontal position and with one edge of the roller projecting outwardly beyond the slide.

Each roller is engaged in a seat 49 at the outer edge of a horizontally sliding bolt 50 at the upper and lower edges of door 6 and each formed with a vertical slot 51 sliding on a pin 52 carried at the adjacent edge of the door. The inner end 53 of the bolt 50 is engaged in a notch 54 in the adjacent bolt 35 or 36 when the latter is moved vertically into its door locking position to thus lock the vertical bolt from retracting movement.

The outer edge of bolt 50 is curved at each side of seat 49, as shown at 55 to guide the roller 46 in position in the seat.

In the operation of the device, with doors 5 and 6 in their unlocked position, as shown in Figure 1, upper and lower vertically sliding bolts 35 and 36 have been retracted by turning pinion 44 in a proper direction so that door 6 is free to swing open. The retracting movement of bolts 35 and 36 slides upper and lower horizontal bolts 50 outwardly of notches 54 to a position with their outer edges substantially flush with the outer edge of door 6.

Rollers 46 and 47 remain seated in their seats 49 in bolts 50 and seats 49 are of proper depth to hold astragal 7 sufficiently entered in slot 8 to seal the meeting edges of the doors, as shown in Figure 6. The rollers and astragal being both carried by the upper and lower slides 9 and 10 are held engaged in seats 49 and slot 8 respectively by spring 47 urging the slides outwardly.

Either of the doors 5 or 6 may be opened by pulling thereon from the inside or pushing thereon from the outside in the usual manner causing rollers 46 and 47 to ride out of their seats 49 and which moves slides 9 and 10 inwardly of door 5 sufficiently to retract astragal 7 from slot 8 to clear door 6. Ends 19 of bell crank levers 20 and 26 are sufficiently free in their slots 18 in slides 9 and 10 to permit retracting movement of the astragal without obstruction by racks 24 and 27 with gear 30 so that rollers 46 and 47 are free to move in and out of their seats 49 when opening and closing the doors, the rollers func-

tioning as latches to hold the doors closed and the astragal sealing the meeting edges of the doors.

The doors are locked by turning pinion 44 in a direction to slide bolts 35 and 36 in their sockets 37 and 39, whereupon springs 17 move slides 9 and 10 outwardly of door 5 and rollers 46 and 47 carried by the slides move the bolts 50 inwardly of door 6 to enter notches 54 and lock bolts 35 and 36.

Pinion 30 is also turned to actuate upper and lower rack bars 24 and 27 in a direction to hold slides 9 and 10 outwardly and key 33 then locks the pinion 30 in that position.

15 The outward movement of slides 9 and 10 also moves astragal 7 fully into slot 8 to further lock the doors to each other.

20 Astragal 7 is formed with a sloping shoulder 56 at its central rear edge engaged by a sloping shoulder 57 on rack bar 24 to brace the center of the astragal when the doors are in a locked position, the shoulders being clear of each other when the rack bar 24 is moved into an unlocked position to provide freedom of movement for the astragal when opening the doors.

25 The slides 9 and 10 and bolts 50 at the top and bottom of the doors are enclosed by cover plates 58 and 59 for each door.

30 In view of the foregoing description taken in conjunction with the accompanying drawings, it is believed that a clear understanding of the device will be quite apparent to those skilled in this art. A more detailed description is accordingly deemed unnecessary.

35 It is to be understood, however, that even though there is herein shown and described a preferred embodiment of the invention the same is susceptible to certain changes fully comprehended by the spirit of the invention as herein described and the scope of the appended claims.

40 Having described the invention, what is described as new is:

45 1. In a pair of swinging doors, one of said doors having a vertical slot at its free edge and the other of said doors having a horizontally movable vertical astragal at its free edge for entering the slot, the improvement comprising the assembly of a roller connected to the astragal for bodily movement therewith, a vertically sliding bolt for locking the first named door, manually operated means carried by the first named door for locking and unlocking said vertically sliding bolt, a horizontally sliding bolt carried by the first named door for locking engagement with the vertically sliding bolt, said horizontal bolt having an arcuate seat for receiving the roller and lockably actuated by a projecting movement of the roller, manual actuating means carried by the second named door for projecting and retracting the roller and astragal, and locking means for said manual actuating means, said manual actuating means including a loose connecting means between the actuating means and the roller to provide limited independent retracting and projecting movement of the roller relative to the actuating means when the latter is unlocked.

50 2. In a swinging closure, a relatively stationary closure structure provided with a vertical slot and a horizontal slot, an astragal carried by the swinging closure structure, means carried by the swinging closure for projecting said astragal into said vertical slot, said swinging closure having a recess, a slide disposed in said recess and having a roller at its outer end, means connecting said slide to said astragal for movement of said slide

and astragal as a unit, and a sliding bolt carried by the relatively stationary structure and having a seat, said sliding bolt being opposed to said slide so that said roller is movable into and out of said seat when said swinging closure is actuated whereby the roller in said seat constitutes a latch.

3. The combination of claim 2 and a spring reacting on said slide opposing the movement of said slide inwardly of said recess.

KURT P. TSCHAEPE.
